UNITED STATES PATENT OFFICE.

CLETUS A. BROWN, OF STUTTGART, ARKANSAS.

DRIVING MECHANISM FOR GRAIN HARVESTERS OR BINDERS.

1,173,926.

Specification of Letters Patent. Patented Feb. 29, 1916.

Application filed March 27, 1914. Serial No. 827,699.

To all whom it may concern:

Be it known that I, CLETUS A. BROWN, a citizen of the United States, residing at Stuttgart, in the county of Arkansas and State of Arkansas, have invented new and useful Improvements in Driving Mechanism for Grain Harvesters or Binders, of which the following is a specification.

This invention relates to improvements in grain harvesters or binders, and particularly to a novel construction of driving mechanism, whereby the binder or harvester may be coupled to a traction engine and driven from the operating mechanism thereof, the primary object of the invention being to provide a novel construction of means for mounting any binder or harvester of the ordinary types in common use and for driving the working parts thereof in a reliable and efficient manner from the tractor.

A further object of the invention is to provide a frame construction and arrangement of drive gearing which is adapted for the mounting of any ordinary type of binder or harvester thereon.

The invention consists of the features of construction, combination and arrangement of parts herein fully described and claimed, reference being had to the accompanying drawings in which:

Figure 1 is a top plan view showing the binder or harvester coupled to a tractor. Fig. 2 is a side elevation of the binder and showing the telescopic driving shaft. Fig. 3 is a longitudinal section on the line 3—3 of Fig. 1. Fig. 4 is a rear elevation of the binder, omitting certain parts of the binder mechanism. Fig. 5 is a longitudinal section on the line 5—5 of Fig. 1. Fig. 6 is a bottom plan view of the binder frame.

Referring to the drawings, 1 designates a traction engine or tractor, which may be of any desired construction, but is preferably of the type shown in my copending application, filed March 27, 1914, Sr. No. 827,698, which tractor is provided with sections 2 and 3 of a driving shaft adapted to be driven from the operating mechanism thereof, said sections being coupled by a universal joint 4; and 5 designates a binder or harvester, which in general may be any of the styles or types in general use, which binder includes the usual reciprocating cutter 6, elevator 7, binder deck or platform 8, and a main driving chain 9 whereby the operating parts thereof are driven, which

chain is ordinarily driven by suitable gearing from the bull wheel.

The frame 10 of the binder may be of ordinary construction, but, in accordance with my invention, the bull and grain wheels are dispensed with and arms or bars 11 are fastened at their forward ends to the frame and provided at their rear ends with bearings 12 for a rear transverse axle 13, on which are journaled supporting wheels 14, having concaved rims 14' on which the binder is adapted to be sustained and travel. The arms 11, as shown, are pivotally connected at their rear ends to the housings or cap portions 15 of the bearing boxes or members 12 by means of links 16, and are coupled at their forward ends to said housings or caps by pivoted bolts 17 provided with adjusting nuts 18, whereby a certain flexibility of connection between the bearing boxes and binder frame is permitted, to adapt the binder to travel over rough ground without objectionable shocks or strain on the binder mechanism proper. The arms or bars 11 may be of a resilient character, to further reduce shocks and vibrations.

In addition to the usual bracing connections between the binder frame, and the binder deck and other superposed portions of the binder mechanism, other braces 19 may connect suitable parts of the superposed framework portions with the housings of the bearing boxes to give increased strength and stability. Fixed in any suitable manner at its rear end to the shaft is a draft beam or bar 20, which is adapted to be coupled at its forward end to the tractor 1 by a suitable flexible coupling connection or universal joint 21, adapted to permit the two structures to have relative vertical and lateral play. When the draft beam is coupled to the tractor the front end of the binder is supported for the operation of the cutter 6 at the proper elevation, the binder being supported at the rear by the wheels 14 on which it travels.

In practice, the frame of an ordinary binder may be modified in accordance with the present invention by simply mounting the parts referred to upon a frame 10, which may be an ordinary binder frame, so as to enable the bull and grain wheels to be dispensed with, the rear supporting axle and wheels mounted in position and the adjusting mechanism arranged as shown. To take

the place of the bull wheel as a driving element, I provide upon the bars of the frame below the binder deck bearings 28 for a shaft section 29 carrying at its rear end a sprocket wheel 30 for driving engagement with the chain 9, the said bearings being provided with suitable housings 31 from which project braces 32 to sustain and reinforce the overlying deck. Another shaft section 33 is coupled to the forward end of the shaft section 29 by a universal joint 34. This shaft section 33 is hollow and of an angular form to telescopically receive the correspondingly shaped solid rear end of the solid angular shaft section 3 on the tractor 1, the respective shaft sections 2, 3, 29, 33 and 35 forming a flexible and extensible shaft which is adjustable longitudinally, vertically and laterally to permit and compensate for relative longitudinal, vertical and lateral play between the tractor and binder, by which an ample range of flexibility of the drive shaft is insured, while a continuous driving action is maintained. Suitable clutch devices 36 and 37 are provided upon the tractor and binder respectively, whereby the driving shaft as a whole may be thrown into and out of action from the tractor or the rear driving section of the shaft thrown out of action from the binder.

From the foregoing description taken in connection with the drawings, the construction and mode of operation of my improved binder support and driving mechanism will be readily understood, and it will be seen that the invention provides means whereby a binder may be readily attached to, and supported and driven from a tractor in such a

manner as to enable the two structures to have ample play to compensate for irregularities in the ground surface, while at the same time enabling power to be continuously transmitted to the binder mechanism in a simple, reliable and efficient manner. It will be obvious that the parts of the invention may be applied to a binder frame structure by simply dispensing with the bull and grain wheels, and substituting therefor the axle supporting arms, axle power delivery sections of the driving shaft and the bracing connections. 50

I claim:—

A binder including a frame made up of longitudinal and transverse bars, a supporting axle, bearings carried by said bars and pivotally engaging the axle, supporting wheels journaled upon the axle, a draft bar pivotally connected with the axle, driving mechanism on the binder including a power delivery shaft, a connection between the frame and forward end of the draft bar, embodying an element slidably engaging one of said parts, a pivotally mounted bell crank lever on the draft bar, a link connecting said lever with the frame, means for locking the lever in different positions to hold the frame 65 at different elevations with relation to the draft bar, and means for flexibly connecting the draft bar with the frame and the said power delivery shaft with a drive shaft of a tractor. 70

In testimony whereof I affix my signature in presence of two witnesses.

CLETUS A. BROWN.
